(57) **CLAIM**

The ornamental design for an electronic vaping device, as shown and described.

DESCRIPTION

FIG. 1 is a perspective view of a new design for an electronic vaping device.

FIG. 2 is a top view of the electronic vaping device of FIG. 1.

FIG. 3 is a bottom view of the electronic vaping device of FIG. 1.

FIG. 4 is a left side view of the electronic vaping device of FIG. 1.

FIG. 5 is a right side view of the electronic vaping device of FIG. 1.

FIG. 6 is a front view of the electronic vaping device of FIG. 1; and,

FIG. 7 is a back view of the electronic vaping device of FIG. 1.

The broken lines in the drawings depict portions of the electronic vaping device that form no part of the claimed design.
